J. VON WALDY

PNEUMATIC SPRING SUSPENSION

Filed March 29, 1924

UNITED STATES PATENT OFFICE.

JULIUS VON WALDY, OF NEW YORK, N. Y.

PNEUMATIC SPRING SUSPENSION.

Application filed March 29, 1924. Serial No. 702,976.

To all whom it may concern:

Be it known that I, JULIUS VON WALDY, a citizen of the United States, and resident of New York, in the county of New York and State of New York, have invented an Improvement in Pneumatic Spring Suspensions, of which the following description, in connection with the accompanying drawings, is a specification, like characters on the drawings representing like parts.

My invention aims to provide an improved pneumatic suspension for motor vehicles and the like.

In the drawing wherein I have shown one illustrative embodiment of the invention,

Fig. 1 is a front elevation showing my improved suspension applied to a well known type of automobile;

Fig. 2 is a central, vertical, sectional view of Fig. 1;

Figs. 3 and 4 are sectional views taken on the lines 3—3 and 4—4, respectively, of Fig. 1; and

Fig. 5 is a fragmentary sectional view taken on the line 5—5 of Fig. 4.

Referring to the illustrative embodiment of my invention, I have shown an improved pneumatic suspension spring 1 preferably made of tubular reinforced rubberized fabric having its ends supported upon suitable brackets 2 mounted upon the vehicle axle 3 and attached at its middle to the vehicle chassis 4.

As shown, the spring 1 may comprise an outer open-ended tubular casing having an inner tube 5 inserted therein. The open ends of the casing are preferably oval in cross section and are provided with reinforced beads 6 adapted to be clamped to the brackets 2 by any suitable and convenient means such as the oval plates 7 removably inserted in the ends of the casing. These plates are adapted to be clamped against the beads to hold them securely against the brackets. To prevent displacement of the beads on the brackets 2, I have shown suitable flanges 8 adapted to telescope over the ends of the casing.

The tubular casing is preferably arched upwards as shown in Figs. 1 and 2 and is reinforced in such a manner as to distribute the load over its entire length by means disposed in or around its walls. To this end I have shown a series of braces, such for

example, as the wires 9 which may conveniently be embedded in the casing wall. Each of the wires 9 is connected at its ends to the reinforced beads 6 of the casing and some of them cross each other midway of the length of the casing as clearly shown in Fig. 5. If desired, some of them may be arranged entirely on each side of the vertical central plane of the casing and from their points of connection to the beads, extend downwardly to the central region of the casing somewhat in the manner of suspension cords curved to conform to the shape of the casing. Others of the cross wires may be connected to the top at one end and to the bottom at the other end of the casing. Due to this arrangement of braces, the general arch shape of the spring is maintained, and under severe shocks and jars the compression thereon places them under tension, at the same time flexing the walls inwardly at the sides, permitting the arch to flex downwardly because of the straightening of the wires or braces thereby permitted.

The upper side of the cushion, as shown, may be shaped to fit in an ordinary channel beam such as is employed in well known makes of automobiles. However, the shape may be varied to adapt the spring for attachment to any automobile chassis. I have shown the casing as having an integral or built-up projection 10 presenting an upper wall of substantial length fitting against and secured to the web of a channel beam of the chassis 4, whereby the chassis frame constitutes a saddle for the spring and the wall against the web and provides the necessary lateral stability of the chassis.

The projection 10 of the casing may conveniently be secured to the chassis frame by any suitable securing means. In the illustrative example I have shown a transverse fastening plate 11 passing through the projection 10 and having openings for clamping bolts such as the bolts 12 at each end which are bolted at their upper ends to a bridge plate 13 across the beam of the chassis 4.

To reinforce the casing 1 adjacent the fastening plate 11 and to prevent this plate from tearing out of the fabric, I have shown reinforcing wires or cords 14 imbedded in the casing around the wall, and a series of reinforcing strands secured to the strands 15 surrounding the fastening plates 11.

These latter strands are preferably continuous whereby to add materially to the strength of the casing.

It will be observed that my improved pneumatic spring is so constructed that it may be substituted for an ordinary steel spring without the necessity of making any changes in either the vehicle chassis or the axle. Thus, I have provided a pneumatic spring that may be manufactured and installed economically and one that will withstand rough usage.

Obviously, my invention is not restricted to the illustrative embodiment herein shown and described but is susceptible of various changes such as those involving alteration, omission, substitution, and reversal of parts.

What I claim and desire to secure by Letters Patent is:

- 20 1. A spring for vehicles comprising a pneumatic elastic beam.
2. A spring for vehicles comprising a pneumatic elastic beam and separated connections between the beam and vehicle.
- 25 3. A spring for vehicles comprising a pneumatic beam adapted to be secured near its ends to the vehicle running gear and supporting the load between its ends.
4. A spring for vehicles comprising a pneumatic beam connected at three points to the vehicle body and the running gear, one point of connection being between the ends of the beam.
- 30 5. A spring for vehicles comprising a pneumatic casing constituting an elongated beam adapted to be secured near its ends to the vehicle axle and midway between its ends to the vehicle frame and means for inflating said casing.
- 35 6. A vehicle spring comprising a pneumatic beam having rigid securing means adjacent the ends and securing means intermediate its ends for connection to the vehicle frame and to the running gear and means associated with the beam for resisting downward flexure.
- 40 7. A spring suspension for vehicles comprising, in combination, an upwardly curved, tubular casing supported solely at its ends upon said brackets, means for connecting said casing midway of the length to the vehicle chassis and reinforcing means associated with the walls of said casing to distribute the load and to permit the desired downward flexure.
- 45 8. A spring suspension for vehicles comprising, in combination, an open ended pneumatic casing supported at its ends on the vehicle axle and secured at its top wall to the vehicle chassis, said casing having reinforcing elements associated with its walls and arranged to be placed under tension due to the load, whereby to resist collapsing and to permit flexure.
- 50 9. A spring suspension for vehicles comprising, in combination, a pair of brackets adapted to be secured to the vehicle axle, an open ended pneumatic casing supported

on said brackets, means connecting said casing directly to the vehicle chassis and reinforcing means for said casing adapted to distribute the load over substantially its entire area, whereby to form a flexible pneumatic beam.

10. A spring suspension for vehicles comprising, in combination, a pair of brackets adapted to be secured to the vehicle axle, an open ended pneumatic arch-shaped casing supported on said brackets, means connecting said casing directly to the vehicle chassis and reinforcing means for said casing adapted to distribute the load over substantially its entire area whereby to form a flexible pneumatic beam.

11. A spring suspension for vehicles comprising, in combination, a pair of brackets secured to the vehicle axle, a tubular pneumatic casing clamped at its ends to said brackets and means for connecting said casing directly to the vehicle chassis.

12. A spring suspension for vehicles comprising, in combination, a pair of brackets secured to the vehicle axle, an open ended, pneumatic casing having reinforcing beads clamped to said brackets and means connecting said casing to the vehicle chassis.

13. A spring suspension for vehicles comprising, in combination, a pair of brackets secured to the vehicle axle, a tubular casing presenting beaded ends adapted to engage said brackets, clamping means removably inserted in said beaded ends and adapted to be secured to said brackets, and means to secure said casing to the vehicle chassis.

14. A spring suspension for vehicles comprising, in combination, brackets secured to the vehicle axle, an upwardly curved, tubular casing supported solely at its ends upon said brackets, means for connecting said casing midway of the length to the vehicle chassis and reinforcing means associated with the walls of said casing to distribute the load and to permit the desired downward flexure.

15. A spring suspension for vehicles comprising, in combination, brackets secured to the vehicle axle, an upwardly curved tubular casing supported solely at its ends upon said brackets, means for connecting said casing midway of the length to the vehicle chassis and reinforcing wires extending throughout the length of said casing and arranged to be placed under tension due to the load whereby to deform the casing walls and permit flexure.

16. A pneumatic spring for vehicles comprising a tubular pneumatic casing adapted to be secured at its ends to a vehicle axle and midway of its length to the vehicle chassis, a plurality of reinforcing wires embedded in the walls of the casing from one end to the other, said wires being ar-

ranged to form suspension cords which, when placed under tension, cause deformation of the casing walls throughout the length of the casing whereby to distribute 5 the load evenly over substantially the entire area of its walls.

17. A pneumatic spring for vehicles comprising a reinforced pneumatic casing, means connecting said casing to the running gear and the chassis of the vehicle, said casing being so arranged as to constitute a flexible pneumatic suspension carrying part of the load by end thrust and part by tension.

18. A pneumatic spring for vehicles comprising, in combination, a tubular casing supported at its ends on the vehicle running gear and having a projection on its upper side adapted to engage a portion of the vehicle chassis and clamping means for securing said projection to the chassis.

19. A pneumatic spring for vehicles comprising, in combination, a pneumatic casing adapted to be connected to the vehicle running gear and to the chassis and securing means for said casing including brackets arranged at its opposite ends and means midway of the length of the casing having a portion embedded therein whereby the casing may be removably connected to the vehicle.

20. A pneumatic spring comprising an elongated tubular casing, tension elements

partly encircling said casing and secured thereto at its ends, and means for inflating said casing with a compressible fluid.

21. A pneumatic spring comprising an elongated tubular casing, the middle on the one hand and ends on the other hand of said casing being provided with means for attachment, one to a supporting and the other to a supported structure, tension elements partly encircling said casing and secured thereto at its ends, and means for inflating said casing with a compressible fluid.

22. A pneumatic spring comprising an elongated tubular casing adapted to be supported horizontally, tension elements partly encircling said casing and secured thereto at its ends, said tension elements being disposed in curves following the contour of said casing having their lowest points at its middle region, and means for inflating said casing with a compressible fluid.

23. A pneumatic spring suspension for vehicles comprising, in combination, the pneumatic casing 1 supported at its ends on the brackets 2 and connected at its top to the channel beam of the chassis 4 of the vehicle, said casing having reinforcing wires 9 embedded therein, all substantially as shown and described.

In testimony whereof, I have signed my name to this specification.

JULIUS VON WALDY.
